SUSIE J. MERCER, Primary Examiner

FIG. 1 is a perspective view of a retroreflective marker for attachment to surfaces adjacent roadways showing my new design;

FIG. 2 is a rear view thereof;

FIG. 3 is a side view thereof, the opposite side having the same appearance.

FIG. 4 is a front view thereof;

FIG. 5 is a top view thereof; and

FIG. 6 is a rear view of an alternate embodiment of my design, the front view of this alternate embodiment being identical to that of the first embodiment.

The oblique line shading indicates the surface of retroreflective structure.
